CLAIM

The ornamental design for a hinge assembly for container, as shown and described.

DESCRIPTION

FIG. 1 is an upper perspective view of a hinge assembly for container;

FIG. 2 is a side view of a hinge assembly for container;

FIG. 3 is a top view of a hinge assembly for container; and,

FIG. 4 is a front view of a hinge assembly for container. The broken lines illustrating a container depict environmental subject matter that form no part of the claimed design.
